IMPROVEMENT IN HAND-LOOMS.

JOHN WHITEHEAD, OF OSKALOOSA, IOWA.

Letters Patent No. 60,305, dated December 4, 1866.

SPECIFICATION.

TO ALL WHOM IT MAY CONCERN:

Be it known that I, JOHN WHITEHEAD, of Oskaloosa, Mahaska county, and State of Iowa, have invented a new and useful Improvement in Loom; and I do hereby declare that the following is a full, clear, and exact description thereof, which will enable others skilled in the art to make and use the same, reference being had to the accompanying drawing, forming part of this specification.

The nature of my invention consists in providing or constructing plates and attaching them to the lathe of a loom so that they may be adjusted in such a manner as to give a light or hard blow, (with the same power applied,) so as to accommodate it to the kind of work that is required to be done. If the work is light the blow or stroke will be light, and if the work is heavy the stroke will also be heavy.

By my invention striped or fancy cloth may be woven by a child rapidly.

To enable others skilled in the art to make and use my invention I will proceed to describe its construction and operation.

Figure 1 is a front elevation of my improved loom.

Figure 2 is a transverse sectional elevation taken from the line *z z*.

Letters of like name and kind refer to like parts in each of the figures.

A represents a frame, made of wood or other material, and to which my improved loom is attached. B is the breast-beam, passing from post to post of the frame and secured thereto, and is located immediately in front of the operator while operating, and when in position upon the seat *c*. D is the lathe, at the end of which are a series of shuttle-boxes, *y y*, located in a frame, one above the other, and so arranged that they may be raised or lowered as desired by means of cords and lever *E a a*, so that a number of shuttles may be used at the same time, each shuttle containing different colors of yarn. This series of shuttle-boxes is made to slide up and down upon rods *F F*, and the boxes are suspended to the cords *a a*, which are attached to the lever *E*. G is the shuttle-board, which extends from side to side of the lathe and connects with the shuttle-boxes at each side of the said lathe. H H are the harness-frames, which are suspended by cords *I I*, attached to what are commonly termed jacks, and designated by the letter *J J*. K is the cloth-beam, around which the cloth is wound or taken up as it is woven. At the end of the cloth-beam is a ratchet-wheel provided with a lever and pawl and detent *N*. These are for the purposes of taking up the cloth and straining the warp sufficiently for weaving. O is the yarn or warp-beam, which is also provided with a ratchet-wheel *P* and pawl *Q*, which is also used for the purpose of letting off the yarn which is represented in red lines, fig. 2. R R are the treadles, which are attached by a joint to the bottom of the legs of the seat or stool, and the other ends are suspended by a cord attached to the levers *S S*, as shown in dotted lines, fig. 1. The ends of these said levers *S S* are also attached to cords *T T*. The cross-beam of the lathe is provided with an adjustable flanged strap or plate *b b*, fig. 2, which fits in corresponding notches in other plates, *c c*. The said plates *c c* are secured upon the top of the frame *A*. The plates *b b* are made adjustable in order that the lay may be set further or nearer to its axis of motion or bearing-point on the frame, so that the lay may be made to beat up the weft or filling with more or less force, owing to the quality of the cloth being manufactured. Heavy work requires a heavy, and light work a light stroke. V is a post provided with a notch for the purpose of retaining and guiding the direction of the lever. The said post is attached to the lathe-beam *D*. W W are two springs attached to the two back posts of the frame *A*. At the end of the said springs are attached cords that connect with the lathe for the purpose of relieving the lathe from any surging, so that the stroke may be softer, and to assist in drawing back the lathe after it has given the stroke.

Having thus described my invention, what I claim as new, and desire to secure by Letters Patent, is—

The combination of the adjustable flanged plates *b b* attached to the lay, and the notched plates *c c*, applied to the top of the loom-framing, as herein described and for the purpose set forth.

JOHN WHITEHEAD.
